UNITED STATES PATENT OFFICE.

ERNEST LE ROY HARDING, OF THREE RIVERS, QUEBEC, CANADA.

ADJUSTABLE WORKTABLE FOR ADDING MACHINES AND ADDING-MACHINE STANDS.

Application filed August 23, 1923. Serial No. 659,004.

To all whom it may concern:

Be it known that I, ERNEST L. HARDING, a citizen of the United States, residing at Three Rivers, in the county of St. Maurice,

5 Province of Quebec, Canada, have invented certain new and useful Improvements in Adjustable Worktables for Adding Machines and Adding-Machine Stands, of which the following is a specification.

10 This invention relates to improvements in adding machines and adding-machine stands, more particularly of the "Burroughs" type, in which a table is so arranged as to be capable of being conveniently and 15 quickly moved into various positions over and clear of the keyboard by the operator of the adding machine, and my objects are:—

First, to provide a table upon which 20 papers may be laid near at hand to the operator,

Second, to reduce the probability of error in transferring written figures to type, due to the present necessity of the operator constantly turning his eyes from his written 25 notes to the adding machine keyboard.

Third, to increase the efficiency of the operator and of the adding machine by conveniently and mechanically bringing such 30 written figures as may require to be typed, and the machine keyboard, into the focus of the eyes of the operator simultaneously.

I attain these objects by the mechanism illustrated in the accompanying drawings, 35 in which—

Fig. 1 is a front elevation of an adding machine and a stand showing my device mounted to the left of the adding machine keyboard.

40 Fig. 2 is an elevation showing the left side and is a projection of Fig. 1.

Fig. 3 is an elevation showing the back of the machine as an inverted projection of Fig. 1 and more particularly showing the various members of my device.

45 Fig. 4 is a left side elevation showing the table in the "down" position.

Fig. 5 is a side elevation of the supporting member 22, Fig. 3, in detail.

50 Fig. 6 is a projection of Fig. 5, a section of the member 22 being shown with the trigger mechanism shown full, in the position it is intended to assume with the catch released. The tube 23 is shown full, a portion shown broken for clarity.

55 Fig. 7 is a section of the casting 25, Fig.

5, the section taken as designated by section line and in the direction of the arrows Y Y, Fig. 5.

The adding machine and its stand are 60 shown dotted in all views and form no part of my invention. Similar numbers refer to similar parts throughout.

The table 6, Fig. 1, is supported by the straps or supports 7 and 8, Fig. 3. The 65 straps 7 are fastened to the under side of the table 6 and are terminated at each extremity by eyes to receive the guides 9 and 10. The support 8, Fig. 3, is a flat strap riveted to the under side of the table 6 and 70 having a hole to receive the guide 9, Fig. 3. The function of the strap 8 is to steady the guide 9 and preserve its relation to the table 6. The eyes of the straps 7 are drilled and 75 tapped to receive set screws marked 11, Fig. 3, which bear against the guide 9 causing it to move with the table 6. The spacing between the straps 7, and between the strap 7 and 8 limits the travel of the table 6.

The guide 10, however, is fixed in relation 80 to the stand or machine, and the eyes in the straps 7 shown at 13, having no set screws, allow the table to move freely along it.

The guide 10 is rigidly fastened to the 85 machine stand by the members 14, 15 and 16, Fig. 1, of which 14 and 15 may be extensions of the machine stand frame, and a part of it, or may be bored to a true fit and secured by means of set screws at 18 as I 90 have shown it. The other ends of the members 14 and 15 are bored to receive the guide 10, the eye in the member 14 being fitted with a set screw 19 to hold the guide 10 rigid.

The member 16 is a brace, which I have 95 shown bolted to the machine stand frame at 20, and supporting the guide 10 at its other extremity holding said guide rigid by means of an eye and set screw 21, Fig. 3. The offset of the brace 16 is determined by the desired travel of the table 6. For the same reason the offset in the member 14 is limited.

The member 22, Fig. 3, is a Y-shaped support for the table, and is shown in detail in Fig. 5. The branches 22^a and 22^b terminate 105 in eyes to receive the guide 9, Fig. 3, of such diameter as to allow the guide 9, which is fastened to the table 6, to move freely through them. The branch marked 22^a is hollow as portrayed in Fig. 6, the inside diameter being such as to make a sliding fit 110 over the rod, or tube 23, Fig. 6, as it is de-

sired to take advantage of the cushioning effect of the air slowly escaping from 22^a. A standard adjustable air check valve of a suitable size may be inserted in either 22^a or 5 the tube 23.

The member 22, Fig. 6, carries a hollow spur 22^c, the free end of which is fitted with a pipe cap 22^d. The pipe cap 22^d is bored 10 to admit the plunger 22^e. The spur contains a spring 22^f and the plunger 22^e which 15 form a trigger arrangement or latch to permit the member 22, Fig. 1, and consequently the back side of the table 6 (through the guide 9 and the straps 7 and 8) to be raised 20 and lowered along the rod 23 at the will of the operator.

The rod or tube 23 is fastened to the adding machine frame at 24 by some means which will permit it to move slightly about 25 an axis at the point of contact with the machine frame, and which I have shown as a stud 24 secured to the machine frame. If the member 23 is a tube, the lower end must be sealed air tight. It is also connected to 30 the frame of the machine stand by means of the casting 25 shown in detail in Figs. 5, 6 and 7 which casting is of such construction as to permit the free movement of the rod 23 through hole 25^a, Fig. 7, and also free movement of the casting 25 itself along the brace 35 of the machine stand frame as shown in Figs. 2 and 4 through the hole 25^b.

The plunger 22^e, Fig. 6, is fitted with a trigger release 26, which, connected by the 40 rod 27 to the plunger 22^e permits withdrawing said plunger against the pressure of the spring 22^f and allows the member 22 to fall along the rod 23, easily and gently against the air compressed in 22^a, consequently lowering the back-side of the table through an 45 arc about an axis through the center line of the guide 10, that is from the position of the table shown in Fig. 2 to that shown in Fig. 4. But this action can only be accomplished when the table 6 is moved to such a 50 position as to be clear of the adding machine keyboard, on account of the guard 28, Fig. 3, which is firmly riveted to the straps 7 and which does not permit of the trigger 55 26 being operated until the table 6 is free of the keyboard of the machine. The table is raised by lifting the back end until the plunger 22^e clears the rod 23, when it will prevent the table falling until the trigger 26 60 is operated. The sides of the rod 23 and the end of the member 22^e where they come in mutual contact, to be plain, thus giving the operator the choice of any two positions of the table between the limits above-mentioned, these positions being governed by 65 the length of the rod 23 which is cut to conform to his choice of positions, which for any one rod, will in this case be its highest and its lowest positions. The mechanism employed to hold the table in an elevated

position, namely members 22^c, 22^d, 22^e, 22^f, has been referred to in divers places throughout the specifications and claims as both "latch" and "trigger", with the distinction that the table, when elevated, is held in 70 that position by the "latch" 22^c and is also released from that position, and allowed to fall by the "trigger" 22^e.

In accordance with the provisions of the patent statutes, I have herein described the principle of operation of my invention, together with the apparatus which I now consider to represent the best embodiment thereof, but I desire to have it understood that the apparatus shown is only illustrative 80 and that the invention can be carried out by other means. Also, while it is designed to use the various features and elements in the combination and relations described, some of these may be altered and others omitted 85 without interfering with the more general results outlined and the invention extends to such use.

Having described my invention, what I claim and desire to secure by Letters Patent 90 is:—

1. The combination with an adding machine and adding machine stand, of a flat table, supported on suitable guides, with means of changing the inclination of the 95 plane surface of said table to any angle about an axis parallel to said guides, and means of locking said table at a plurality of positions within the limits of 0° and 90° upward toward the vertical from the normal 100 horizontal plane of said table, and means of sliding said table along said guides and over the keyboard, and means of preventing said table from changing its elevation or inclination except at predetermined positions along 105 said guides, and then only at the will of the operator.

2. The combination with a structure such as recited in claim 1, of means of locking the table of said structure at a plurality of 110 positions within the limits of 0° and 90° upward toward the vertical from the normal horizontal plane of said table, comprising an adjustable support and a catch working against a spring.

3. The combination, with an adding machine having a table such as recited in claim 1, of means of lowering said table, comprising a tube, a piston, and a check valve.

4. The combination, with a table such as recited in claim 1, of means of lowering said table, comprising a tube sliding upon a rod.

5. The combination, with an adding machine, of a table and means of moving said table over the adding machine keyboard, comprising sliding guides, and fixed guides, said table sliding thereon.

ERNEST LE ROY HARDING
